CLAIM

The ornamental design for a wiper transport system for poultry parts, as shown and described.

DESCRIPTION

FIG. 1 is a top perspective view of a wiper transport system for poultry parts;

FIG. 2 is a bottom perspective view of the design as shown in FIG. 1;

FIG. 3 is a side view of the design as shown in FIG. 1;
FIG. 4 is a rear view of the design as shown in FIG. 1;
FIG. 5 is a front view of the design as shown in FIG. 1;
FIG. 6 is a top and rear-facing perspective view of the design as shown in FIG. 1;

FIG. 7 is a bottom and front-facing perspective view of the design as shown in FIG. 1;

FIG. 8 is a bottom view of the design as shown in FIG. 1;
FIG. 9 is a top view of the design as shown in FIG. 1;

FIG. 10 is a side view of the design as shown in FIG. 1, as shown from the opposing view as shown in FIG. 3;

FIG. 11 is another bottom perspective view of the design as shown in FIG. 1; and,

FIG. 12 is another top perspective view of the design as shown in FIG. 1.
